UNITED STATES PATENT OFFICE

2,349,354

ELECTRIC SWITCH

Wilber M. Johnson, Cleveland Heights, Ohio, assignor to General Electric Company, a corporation of New York

Application June 1, 1942, Serial No. 445,530

3 Claims. (Cl. 200—152)

My invention relates to fluid flow electric switches of the type comprising a pair of cup-like, electrically conducting, metal members electrically insulated from and hermetically sealed to one another by a relatively thin ring of glass to form an enclosure for a quantity of conducting fluid, such as mercury. In the usual form of such switches a barrier of arc resisting, electrically insulating material is disposed between the metal members to divide the interior of the switch into chambers. The chambers are connected by an aperture in the barrier through which the mercury flows to electrically connect the metal members in the circuit making position of the switch. The switch is mounted with the glass ring in a vertical plane and is moved from a circuit making to a circuit breaking position by rotating the switch in said plane to raise the aperture above the level of the mercury thus interrupting the conducting path between the metal members.

An object of my invention is to provide a switch of the above type which may be mounted with the glass ring in a horizontal plane to close the electrically conducting path in the switch and which is moved from a closed circuit position to an open circuit position by tilting the switch at an angle to the horizontal. Another object of my invention is to provide such a switch in which the maximum angle to the horizontal to which the switch may be tilted without breaking the conducting path between the metal members may be selected to suit the intended use of the switch. Another object of my invention is to provide such a switch which is useful in electric lamps of the portable, self-contained, battery operated type commonly known as flashlights to automatically extinguish the lamp in predetermined positions thereof. Another object of my invention is to provide a flashlight switch for controlling the flow of current in the circuit of the flashlight whereby the latter can project only a horizontally or downwardly directed beam of light. A further object of my invention is to provide such a switch of simple structure readily incorporated into and removed from commercially available flashlights and other electrical apparatus without changing the structure or arrangement of the component parts thereof.

Further objects and advantages of my invention will appear from the following detailed description of species thereof and from the accompanying drawing, in which Fig. 1 is a side elevational, partly sectional view of a commercially available flashlight showing a species of switch embodying my invention incorporated therein;

Fig. 2 is a side elevational, sectional view of the species of switch shown in Fig. 1; and Fig. 3 is a similar view of another species of switch embodying my invention. Like numbers denote like parts in the drawing.

Referring to Fig. 1 of the drawing, the flashlight 10 is of conventional type comprising a tubular metal casing 11 having a screw cap 12 provided with a spring 13. The opposite end of said casing 11 is provided with a similar screw cap 14 having a light-transmitting member 15 secured thereto and enclosing a reflector provided with a socket for supporting an incandescent lamp in the usual manner. An elongated electric storage battery 16 of conventional type having two terminals is held in said casing 11 by the clamping action of the screw caps 12 and 14 and the spring 13. The electrical circuit including the battery 16 and the incandescent lamp 15 may be made and broken by the manually operated switch 17 and also includes the spring 13 and the casing 11. The flashlight projects a beam of light coaxial with the casing 11. Further description of the structural details and operation of the flashlight 10 is deemed unnecessary since these are well known.

A mercury switch 18 is disposed between spring 13 and the battery 16 of the flashlight illustrated in Fig. 1. The switch 18 is in its circuit making position when the beam projected by the flashlight is directed vertically downward. In accordance with my invention the switch 18 may be so constructed and arranged that it is not moved from its circuit making to its circuit breaking position until the axis of the downwardly projected beam is directed beyond a predetermined angle to the vertical. This angle may be selected as desired up to and including ninety degrees to the vertical which would be horizontal. Thus, the beam may be directed at angles smaller than the predetermined angle but cannot be inadvertently directed upward beyond the selected angle. This is advantageous in many locations, such as in theaters or the like.

In Fig. 2 of the drawing I have shown in its circuit making position a species of switch 18 useful in the flashlight illustrated in Fig. 1. The switch 18 comprises a pair of cup-shaped or dished metal members 19 and 20 so shaped and juxtaposed as to form an enclosed space between them. These members 19 and 20 have flanges 21 and 22, respectively, and are spaced from one another by an annular spacer 23 having a peripheral portion 24 interposed between said flanges 21 and 22. Said spacer 23 consists of

electrically insulating material, which may be magnesia or alumina. The annular groove or slot formed by the portion 24 and the flanges 21 and 22 is filled with a ring 25 of glass or similar thermoplastic material which is fused to flanges 21 and 22 to form a hermetically tight, mechanically strong joint therebetween. The switch 18 contains a quantity of mercury 26, or equivalent material, and preferably is filled with a gas, such as hydrogen, at substantial pressure through the opening 27 in said member 19 during manufacture. The opening 27 is hermetically sealed by fusion welding a metal closure member 28 therein. Similar switches in which a perforated barrier is disposed between the members 19 and 20 instead of the annular spacer 23 of my invention are described in the U. S. Patents 2,101,092, issued December 7, 1937, and 2,175,306, issued October 10, 1939.

The inner surface 29 of the annular spacer 23 has a frusto-conical shape. The reentrant portion 30 of the member 19 and the reentrant portion 31 of the member 20 are contiguous with said surface 29. The spacer 23 engages the members 19 and 20 over a substantial area to strengthen the switch against forces tending to press said members 19 and 20 together. A metal wire 32 is secured, as by welding, to said reentrant portion 30 and terminates adjacent the reentrant portion 31. In the circuit making position of the switch 18, shown in Figs. 1 and 2, the mercury 26 bridges the gap between the end of wire 32 and the inner surface of portion 31. The ring 25 is then in a horizontal plane. Circuit interruption takes place when the switch is tilted so that the mercury 26 does not bridge this gap or the gap between the inner surface of the reentrant portion 31 and the reentrant portion 30. The maximum angle to the horizontal to which the switch 18 may be tilted without causing circuit interruption is determined by the relation between the quantity of mercury 26, the size of these gaps and the slope of the inner surface of spacer 23. If, for example, the said inner surface is of cylindrical shape and the quantity of mercury 26 together with the aforesaid gap is properly selected, then the said maximum angle may be as great as 90° to the horizontal. Of course, the maximum angle of tilt may be changed as desired to suit the needs of the user. In the switch illustrated in Fig. 2, the said maximum angle is considerably less than 90°.

The switch illustrated in Fig. 3 of the drawing is similar to that described above and shown in Fig. 2. In this embodiment, however, the lower wall member 33 is in the form of a dish having a sloping surface 34 and a rounded reentrant portion 35. The closure member 28 is in said portion 35. The lower end portion of the wire 32 is in the form of a ring 36 disposed in the annular space between the surface 34 and the rounded portion 35 and is spaced from the inner surface of the member 33. The mercury 26 bridges the gap between the ring 36 and the member 33 in the circuit making position of the switch. The lower surface of the spacer 23 in this embodiment is in a plane including the upper surface of the member 33 and extends inwardly to form a stop or shoulder to limit the movement of the mercury 26 when the switch is tilted. Thus, the mercury 26 cannot bridge the members 19 and 33 when the switch is tilted. As in the embodiment illustrated in Fig. 2 the slope of the surface 34, the quantity of mercury 26 and the size of the gap between the ring 36 and the inner surface of the member 33

determine the maximum angle to the horizontal to which the switch may be tilted without interrupting the circuit in which it is included. In this embodiment the said maximum angle is also less than 90° to the horizontal.

The switches illustrated in Figs. 2 and 3 are readily incorporated into and removed from the flashlight illustrated in Fig. 1 by removing the cap 12 of the flashlight, inserting the switch in proper position against the battery 16 and replacing the cap 12. The switch is engaged and held in proper position by the spring 13 in the reentrant portion 30 of the member 19. The different configuration of the wall members 19, 20 and 33 facilitates mounting of the switches in proper position in the flashlight particularly in the dark when the sense of touch alone can be used. The position of the switch may be reversed when an upward beam is desired. The switches of Figs. 1 and 2 may be disposed in the flashlight between the battery 16 and the center contact of the lamp base, when desired.

It will be understood, of course, that I contemplate the use of my improved fluid flow switch in other types of flashlights and electrical apparatus. For example, flashlights projecting a beam of light having an axis normal to the longitudinal axis of the battery enclosing part of the flashlight are well known in commerce. In such flashlights the switch is effectively disposed between the center contact of the lamp base and the battery with the plane of the glass ring normal to the beam axis.

What I claim as new and desire to secure by Letters Patent of the United States is:

1. An electric, fluid flow switch comprising spaced, shallow, dish-shaped, electrically conducting wall members having substantially planar, parallel, peripheral portions hermetically joined by a thin ring of electrically insulating material to form an enclosure of substantially greater diameter than depth, an electrically insulating annular spacer in said enclosure engaging said wall members and having an opening substantially smaller in diameter than that of said enclosure and defining, with said wall members, a cavity in said switch, a solid contact member supported in said cavity by one of said wall members and terminating adjacent the other of said wall members, and sufficient mercury in said cavity to bridge the space between said contact member and the adjacent wall member in one position of said switch, the cavity-defining surface of said spacer providing a path for mercury flow of greater length than the distance between the peripheral portions of said wall members and of sufficient length with respect to the quantity of said mercury to prevent said mercury bridging the space between said wall members in any position of said switch.

2. An electric, fluid flow switch comprising spaced, shallow, dish-shaped, electrically conducting wall members having substantially planar, parallel, peripheral portions hermetically joined by a thin ring of electrically insulating material to form an enclosure of substantially greater diameter than depth, an electrically insulating annular spacer in said enclosure engaging said wall members and having an opening substantially smaller in diameter than that of said enclosure and defining, with said wall members, a cavity in said switch, a solid contact member supported in said cavity by one of said wall members and terminating adjacent the other of said wall members, and sufficient mercury in said

cavity to bridge the space between said contact member and the adjacent wall member in one position of said switch, the cavity-defining surface of said spacer having a planar portion parallel with the planar peripheral portions of the wall members and a cylindrical portion with its longitudinal axis substantially normal to the planar portion, said surface providing a path for mercury flow of greater length than the distance between the peripheral portions of said wall members and of sufficient length with respect to the quantity of said mercury to prevent said mercury bridging the space between said wall members in any position of said switch.

3. A mercury switch comprising a pair of opposed metal discs spaced a short distance apart, 15 an annular spacer of insulating material filling

the space between said discs except for the central opening in said annular spacer, said opening being tapered so as to define a frustro-conical cavity bounded at its ends by center portions of said discs, a contact secured to the center portion of the disc defining the larger base of the cavity and extending axially of the cavity to within a short distance of the center portion of that disc which defines the smaller base of the cavity, and a quantity of mercury in said cavity sufficiently large to bridge the gap between said contact and the said disc which defines the smaller base when said smaller base is lowermost and horizontal, said quantity of mercury being insufficient to bridge the space between the said center portions of the discs in any position of the switch.

WILBER M. JOHNSON.
